UNITED STATES PATENT OFFICE.

JOSEPH S. NEWMAN, OF CLEVELAND, OHIO, ASSIGNOR TO THE ELECTRO SET COMPANY, OF CLEVELAND, OHIO, A CORPORATION OF OHIO.

TOY TELEPHONE SYSTEM.

1,239,508.

Specification of Letters Patent. Patented Sept. 11, 1917.

Application filed November 17, 1915. Serial No. 61,875.

To all whom it may concern:

Be it known that I, JOSEPH S. NEWMAN, a citizen of the United States, residing at Cleveland, in the county of Cuyahoga and 5 State of Ohio, have invented a certain new and useful Improvement in Toy Telephone Systems, of which the following is a full, clear, and exact description, reference being had to the accompanying drawings.

10 This invention has to do with toy telephone systems, and relates particularly to a connection block whereby the electric circuit of a toy telephone system may be quickly and correctly made by inexperienced persons, and without the need of any further explanation than that appearing on 15 the connection block in the form of a single word applied to each pair of binding posts and designating the instrument or element 20 of the system whose terminals are to be attached thereto.

In my copending application Serial No. 45,628, filed August 16, 1915, there is shown a toy telephone set wherewith my present 25 invention is especially suitable for use, for it is the purpose of my several inventions to so cheapen a telephone outfit that the same may be sold as a toy, and to simplify it to such an extent that a child who can 30 read the inscriptions on the connection block will experience no difficulty in properly arranging the circuits.

By reason of the particular arrangement of connections embodied in the block, a very 35 simple telephone circuit is made possible wherein only two line wires are required instead of the usual three, the extra wire ordinarily forming one side of the bell circuit.

Therefore, among the objects of my invention is the provision of a simplified telephone circuit that is peculiarly adapted to 40 toy telephone systems.

A further object of the invention is the provision of an instrument, herein referred 45 to as a connection block, that is constructed preferably of wood so as to avoid the need of insulating material and consequently resulting in a very cheap production of the instrument, and by the use of which instrument, and by the use of which instru- 50 ment the above ends are efficaciously attained in a simple and expeditious manner.

Other objects will become apparent as I proceed to describe, in detail, the circuit and connection block embodying my invention and illustrated in the accompanying drawing which forms a part hereof, and wherein Figure 1 is a perspective view of the connection block; Fig. 2 is a bottom plan thereof; and Fig. 3 is a diagram of a toy circuit including two of my connection blocks and 60 arranged in accordance with my invention.

The body portion 1 of the connection block is preferably formed of a rectangular block of wood having its underneath surface recessed from end to end as shown at 2, leaving a pair of ribs 3 extending along each side of the block. The particular design of the block is of considerable importance, for it allows the material from which the blocks are made to be formed up in long strips by 70 simply grooving the strip on one side to give it the channel formation, and then sawing the strip into blocks of the required length.

The binding posts 5 are preferably formed 75 of ordinary brass brads that are driven through the block until their points project a slight distance into the recess 2. Two pairs of binding posts are arranged at one end of the block, the one being designated 80 "Trans," meaning that they are for attachment to the transmitting instrument of the telephone set, and the other pair is marked "Bat," and is adapted to have connection with the terminals of the battery. On the 85 left hand side of the block, about midway of its length, there is located a pair of binding posts marked "Rec," arranged to have connected to them the terminals of the receiver, and directly opposite the receiver 90 binding posts is a pair of posts marked "Bell" to which the terminals of an electric bell are attached. On the same side of the block, and located at the end remote from the battery binding posts, is a pair of posts 95 marked "Line." To each of these is connected one of the line wires. A switch blade 6 of thin spring brass is pivoted upon a brad 7 that extends through the block and into the channel 2. The free end of the switch blade is 100 adapted to cooperate with contact points marked "T," "R" and "L." These contact

points are formed by the heads of brads that are driven through the block and cut off at suitable lengths so that their ends are protected within the channel 2. Other 5 brads 8 and 9, which have no electrical function, are driven into the block to form stops to limit the throw of the switch blade.

Upon referring to the bottom plan view of Fig. 2, it will be seen that a wire 10 connects one of the transmitter binding posts to one of the pair designated "Rec;" while the other post of the transmitter pair is connected, by the wire 11, to one of the battery binding posts and to the contact-point 10 "R." The other "Bat" binding post has connection with one of the "Bell" posts, and with a "Line" post, through the wire 12, the opposite "Line" post having connection with the switch blade 6, through the wire 13 and brad 7. The contact-point "T" has connection through the wire 14, with the remaining binding post of the "Rec" pair; and the remaining "Bell" post is connected, 15 through the wire 15, with the contact point "L." For the sake of durability and cheapness I prefer to solder the aforesaid wires 10 to 15 to the respective binding posts; and these connections are effectually protected 20 because they are contained within the recess 2.

In the diagram of Fig. 3 I have shown, conventionally, the elements of a two-station toy telephone system properly connected by the use of my connecting blocks; the transmitting instrument 20, receiver 21, battery 22, and bell 23 of each station having each its terminals connected to the appropriate pair of binding posts of its respective connection block 1. The connection of the terminals with the binding posts may be conveniently made by twisting the terminals about the posts. The "Line" binding posts of the blocks of both stations are connected through the line wires 24 and 25.

When not in use, the switch blades 6 of the two stations A and B rest upon the contact points marked "L" which indicates line. For the purpose of describing the operation of the instrument and circuits, let it be assumed that station A desires to call B. The operator turns the switch blade into engagement with the contact point "R," which indicates "ring" and a circuit is established from the battery 22 of the A station through the wire 11, contact point "R," switch blade 6, brad 7, wire 13, line wire 25, wire 12 of the connection block of station B, through the bell 23 of said station, back to the switch thereof and through the other line wire 24, the wire 12 of the connection block of station A, to the opposite side of the battery 22. The operator at station B responding to the call, throws the switch of his connection block to the contact point

marked "T," which represents the "talking" 65 circuit, the operator at station A doing likewise. This breaks the bell circuit and establishes a circuit from battery 22 of station A, through wire 11, the transmitting instrument, wire 10, the receiver 21, wire 14, contact point "T," switch blade 6, wire 13, line wire 25, through the corresponding circuit of the connection block of station B, including the receiver, transmitter, and battery of 70 that station, and returning through the line wire 24, and wire 12 of the first connection block, to the battery 22 of station A. 75

From the foregoing description it will be seen that a very simple telephone circuit is 80 made possible by virtue of my connection block; and it will also be appreciated, from the structural details of the connection block, that the same may be produced at a very low cost.

Having thus described my invention, 85 what I claim is:

1. A device of the kind described, comprising a block having means for connecting the elements of a telephone set, said connections being indicated, said block also having line wire connections whereby two sets may be electrically connected, contacts located in the signal, talking and battery connections, and a switch connected with the line and adapted to engage any one of 90 said contacts, whereby the circuit through the line may be made to include the signal connections, or the battery connections, or the battery and talking connections. 95

2. As a new article of manufacture, a block 100 having connecting means for the battery, the talking, and the signal elements of a telephone set; connections between said means whereby the elements are placed in proper relation; contacts within said connections, one for the battery, one for the signal, and one common to both the battery and talking elements; a switch for engagement with any one of said contacts; the block having also line wire connecting means; connections between one of the line wire connecting means and the switch; and connections between the other line wire connecting means and all of the connecting means of the aforesaid elements. 105

3. The combination of two blocks each having connecting means for the battery, the talking, and the signal elements of a telephone set; connections between said means whereby the elements are placed in proper relation; contacts within said connections, one for the battery, one for the signal, and one common to both the battery and talking elements; a switch for engagement with any one of said contacts; each block having also line wire connecting means whereby the blocks may be electrically connected; connections between one of 110 115 120 125

the line wire connecting means of each block and its respective switch; and connections between the other line wire connecting means of said block and all of the connecting means of the elements of its respective telephone set; the switch of each block being adapted to engage its signal contact and

to send a signal to the telephone set of the other block, and then to engage its talking contact to establish a talking circuit between 10 the telephone sets.

In testimony whereof I hereunto affix my signature.

JOSEPH S. NEWMAN.
